DAVID DE SANTO, OF NEW ROCHELLE, NEW YORK, ASSIGNOR TO THE WILKES-CASEY ENGINEERING AND CONTRACTING COMPANY INCORPORATED, OF NEW ROCHELLE, NEW YORK, A CORPORATION OF NEW YORK.

BUCKET TRIP FOR STEAM EXCAVATORS.

Application filed August 1, 1921. Serial No. 488,784.

To all whom it may concern:

Be it known that I, DAVID DE SANTO, a citizen of the United States, residing in the city of New Rochelle, in the State of New York, have invented certain new and useful Improvements in Bucket Trips for Steam Excavators, of which the following is a specification, reference being had to the accompanying drawing, forming a part hereof.

In the ordinary use of steam shovels or excavators rapid operation requires the services of a special man to trip the bucket or scoop when it is in position to discharge its load. For this purpose a rope is run from the trip, over suitable guides, to some convenient point where it can be grasped by the hands, a sharp pull being required for the release of the trip. At this time the hands of the engineer are usually otherwise engaged and much time is lost if he is required to shift his hands to the trip rope.

It is the object of this invention to provide means whereby the trip rope is operated automatically, the operating means being brought into action at the proper time by the application of one foot of the engineer to a pedal, without requiring him to remove his hands from the controlling levers. In accordance with the invention the trip rope, connected to the trip and led over suitable guides as usual, is arranged so that it is drawn out during the outward movement of the bucket or scoop and is held under such tension that there shall be no slack, the tension, however, being insufficient to trip the bucket. Means are provided whereby the drawing out of the trip rope can be stopped at any time, whereby the continued outward movement of the bucket, under its own momentum or by the outhaul cable, will cause a sharp pull to be placed on the trip rope, sufficient to release the trip. This action is brought about by the engineer just before the bucket reaches the point of discharge, having then a further movement of a few inches which is sufficient to effect the release of the trip. The invention will be more fully explained hereinafter with reference to the accompanying drawing in which it is illustrated and in which—

Figure 1 is a view mainly in side elevation of an excavator to which the invention is applied.

Figures 2 and 3 are detail views of parts 55 to be referred to.

In the drawing there is shown only so much of an excavator of ordinary construction as is necessary to enable the invention to be understood, and these parts may be 60 of any usual or suitable construction. As shown in the drawing the excavator is provided with a boom *a* pivoted, as at *b*, to the frame *c* of the excavator, so that the boom can be raised and lowered and swung to one 65 side or the other as required in the operation of the excavator. The bucket or scoop *d* has its bottom *d'* hinged in the usual manner and provided, as at *d''*, with a trip which normally holds the bottom in closed position 70 but can be disengaged by a sharp pull so as to release the bottom and permit the load to be discharged. The bucket or scoop is hung from the boom by a suitable trolley *d''*, so that it can be moved readily upon the 75 boom, either in or out, by the usual means under the control of the engineer. As shown, an outhaul cable *e*, connected to the bucket *d*, passes over a guide sheave *a'* at the outer end of the boom *a* and thence, over other 80 suitable guide sheaves, to a drum *e'* operated from the engine under the control of the engineer in the usual manner. A hoisting cable *f*, connected at one end to the frame *c*, as at *c'*, passes over a guide sheave *a''* on the 85 boom and thence, over other suitable guide sheaves, to a drum *f'*, also operated by the engine under the control of the engineer in the usual manner, for the purpose of raising and lowering the boom.

The engineer stands upon a foot board or floor *c''*, facing to the front, with his hands in position on the controlling levers. The trip rope *g*, connected to the trip *d''* of the bucket or scoop *d*, is drawn out by the outward movement of the bucket or scoop and is arranged to be taken up by suitable means such as the means hereinafter described. On or near the foot board *c''*, in position convenient for operation by the foot of the engineer, is placed a device whereby the outward movement of the trip rope, under the influence of the bucket, can be checked at any time and thereby sufficient tension be placed on the trip rope, by the continued 100 outward movement of the bucket or scoop, even for a few inches only, to cause the release of the trip.

Various forms of devices for taking up the slack of the trip rope and for checking its outward movement might be devised, but the devices shown in the drawing are found 5 to be satisfactory for the purpose. As there shown there is mounted in suitable stands h' , erected on the floor a^2 , a drum h , which is free to rotate on its supporting spindle h^2 . The trip rope g is connected to the 10 drum, being wound thereon in one direction, and there is also connected to the drum and wound thereon in the opposite direction, a take-up rope i which, being led over a suitable guide sheave i^2 and connected to the 15 frame as at i^3 , receives, in the bight between the guide sheave and the point of connection i^3 , a counterweight i^4 , carried by a sheave i^5 . The take-up rope i is always under tension, by reason of the counter- 20 weight, and therefore tends to rotate the drum h in a direction to wind thereon the trip rope g , which is led over a guide sheave g' and thence to the trip d^2 . The trip rope g is therefore maintained always under ten- 25 sion, but the tension is insufficient to release the trip. The trip rope is drawn out by the outward movement of the bucket and, when the bucket moves inward, is rewound again on the drum h . As a convenient device for 30 checking the outward movement of the trip rope, so that it shall be held from movement while the bucket continues its movement for a few inches, and the trip be there- 35 by released, the drum is provided with a brake surface h^8 and a brake h^4 is provided to co-operate with the brake surface under the influence of a pedal h^5 , mounted on a pedestal h^6 .

Whenever the engineer desires to dis- 40 charge the load from the bucket, he applies

his foot to the pedal which is conveniently placed before him and thereby stops the rotation of the drum under the influence of the outwardly moving trip rope and checks the trip rope against further movement, 45 whereby the trip is released and the load discharged just as the bucket is brought to rest under the control of the engineer.

It will be understood that various changes in details of construction and arrangement 50 can be made to suit different conditions of use and the convenience of the manufacturer, and that the invention, therefore, is not limited to the particular construction shown and described herein except as pointed out 55 in the claims.

I claim as my invention:

1. In an excavator the combination of a bucket provided with a discharging trip, 60 means to support the bucket for movement, a means to move the bucket on its support, a trip rope connected to the trip, a drum to which the trip rope is connected and wound in one direction thereon, a take-up rope also connected to the drum and wound thereon 65 in the opposite direction, and means to check the rotation of the drum.

2. In an excavator, the combination of a bucket provided with a discharging trip, 70 means to support the bucket for movement, a means to move the bucket on its support, a trip rope connected to the trip, a drum to which the trip rope is connected and wound in one direction thereon, a take-up rope also connected to the drum and wound thereon 75 in the opposite direction, and a brake to check the rotation of the drum.

This specification signed this 27th day of July, A. D. 1921.

DAVID DE SANTO.
